WINDOW CONSTRUCTION OF THE SLIDING
SASH TYPE

Frederick W. Dakin, Montreal, Quebec, Canada

Application April 12, 1950, Serial No. 155,453

3 Claims. (Cl. 189—73)

1

This invention relates to improvements in window constructions of the sliding sash type.

A particular object of this invention is to provide means for guiding the sides of window sashes which can be regulated to adjust frictional contact between the window frame and the sashes to facilitate sliding of the sashes in the window frame.

The main features of this invention reside in the provision of guide flanges along the guiding surface of the sash side rails which slide in preformed grooves provided in compressible guide strips secured to the sides of the window frame at various points along the length of the guide strips by bolts which may be adjusted to apply varying degrees of compression to the guide strips for displacing the compressible material of the guide strips to regulate frictional contact between the side walls of the grooves and the sash guide flanges.

A further feature consists in the provision of a spring balancing of the sashes in conjunction with the frictional guiding of the sashes to facilitate sliding movement of said sashes in the window frame.

Proceeding now to a more detailed description, reference will be had to the accompanying drawings, in which:

Fig. 1 is a sectional view of a portion of a sash and window frame taken through the sash side rails on one side and the adjacent side frame members of a window frame.

Fig. 2 is a view partly in section of the window shown in Fig. 1, taken through the bottom rails of the sashes and showing portions of the sash side rails and adjacent side frame member on one side of the window frame in elevation.

Referring more particularly to the drawings, 5 and 6 generally designate a pair of sash frames of aluminum or other suitable material, each having opposing side rail members 7 provided with parallel guide flanges 8 which project from the side rails to slide in preformed parallel grooves 9 provided in an individual moulded guide strip 10 of rubber or other compressible material for the flanges of each guide rail. The guide strips 10 are butted together in side-by-side relation and extend along the length of a side frame member 11 on each side of a window frame which may be of wood or metal. The guide strips 10 are separately fastened to each frame member 11 by bolts 12 which are passed through openings at various points along the length of each guide strip and are screw-threaded into sockets 13 fitted in each of the side frame members of the window frame.

2

The window frame engaging sides of guide strips 10 are shaped to leave a space, indicated at 14, between the guide strips and the opposing surface of the side frame member 11. The outer side walls 15 of each guide strip 10 are also shaped to be normally spaced from the adjacent end edges of window trims 16 as indicated at 17. Strips 10 are provided with projecting side flanges 18 which overlap trims 16. Flanges 18 are undercut toward the side walls 15 so that only the tips of the flanges normally contact the surface of the trims.

Frictional contact between the guide flanges 8 of the window sashes 5 and 6 and the side walls of the grooves 9 provided in the compressible guide strips 10 may be regulated by screwing the bolts 12 into and out of the sockets 13. When the bolts 12 are screwed into the sockets 13, the heads of the bolts exert pressure on the compressible guide strips 10 and cause the compressible material to be displaced so as to increase the frictional contact between the sash rail guide flanges 8 and the side walls of the grooves 9. In this connection it is pointed out that the portion 20 of the compressible guide strip on either side of the screw is caused to spread in a direction toward the inner adjacent surfaces of sash rail flanges 8. In addition, the inward pressure applied by the bolts 12 causes portions of the compressible material to be displaced into the spaces indicated at 14 and 17. While this displacement is being effected, the flange 18 of guide strip 10 bears against the surface of trim 16, and, due to the undercutting of the flange, causes the portion 21 of the guide strip between said flange 18 and the adjacent sash rail guide flange 8 to bear against the adjacent surface of said sash rail guide flange 8. Displacement of the material into the space indicated at 14 also causes that portion 22 of the guide strips 10 between their abutting surfaces and the adjacent sash guide flange 8 to bear against the adjacent surface of said sash rail guide flange. When it is desired to reduce the frictional contact between the sash rail guide flanges 8 and the side walls of the grooves 9, this is accomplished by loosening the bolts 12 to relieve some of the compression on the compressible guide strips 10 so as to reduce the frictional contact between the side walls of grooves 9 and the surfaces of the sash rail guide flanges 8.

The sashes 5 and 6 are shown to have double glazing panels 24, each glazing panel being embedded in grooves 25 of rubber glazing strips 26 held between a side plate 27 formed integral with the sash frame and a removable side plate 28

which is secured to the opposite side of the sash frame by bolts 29. An insulating strip 30 of rubber is interposed between the adjacent surfaces of said removable side plate 27 and the frame.

Each window sash is balanced by suitable sash balancing means such as the coil spring type balance 31 shown in Fig. 1. The spring is secured at one end to a sash and at its other end to the upper portion of the window frame.

I claim:

1. In a window construction for sliding window sashes, a window frame including side frame members, a sash guide strip made of resilient compressible non-metallic material and arranged along the length of said side frame members, said guide strip being provided with grooves along its length, a window sash including side rail members positioned between said frame members to oppose the guide strip of said frame members and slidably relative thereto, said side rail members being provided with guide flanges sliding in the grooves of said guide strip between and in contact pressure with the opposing side walls and the grooves, and rigid means adjustable for compressing said guide strip to vary the effective contact pressure between said rail flanges and the opposing side walls of said grooves.

2. A window construction as set forth in claim

1, in which the window frame engaging side of said guide strip is inwardly offset from one side edge for a substantial portion of its width to provide a space between a substantial portion of the guide strip and the opposing surface of the side frame member to permit displacement of a portion of said guide strip when the latter is subjected to compression.

3. A window construction as set forth in claim 1, said compressing means including a socket provided in said side frame member and a bolt extending through said guide strip and received in said socket in screw-threaded engagement therewith, said bolt being provided with a flanged head adapted to compress said guide strip when the bolt is screwed into said socket.

FREDERICK W. DAKIN.
